Primary Examiner — Rashida C. Walshon(74) *Attorney, Agent, or Firm* — Schwabe, Williamson & Wyatt, P.C.(57) **CLAIM**

I claim the ornamental design for a shoe, as shown and described.

DESCRIPTION

FIG. 1 is a left side view of a shoe, showing my new design;

FIG. 2 is a front perspective view thereof;

FIG. 3 is a rear perspective view thereof;

FIG. 4 is a right side view thereof; and,

FIG. 5 is a front view thereof.

The broken lines are provided for environmental purposes only and form no part of the claimed design.

1 Claim, 5 Drawing Sheets(56)
